(57) **CLAIM**

The ornamental design for a termite monitoring/bait station, as shown and described.

DESCRIPTION

The article in which the ornamental design of the invention is embodied is intended to function as a termite monitoring/bait station.

FIG. 1 is a top perspective view of the termite monitoring/bait station showing my new design;

FIG. 2 is a top plan view thereof;

FIG. 3 is a front elevation view thereof, with the rear elevation view being identical;

FIG. 4 is a side elevation view thereof, with the opposite side elevation view being identical; and,

FIG. 5 is a bottom plan view.
